ATTORNEY

UNITED STATES PATENT OFFICE.

JOHN P. BROOKE, OF NARBERTH, PENNSYLVANIA, ASSIGNOR TO NILES-BEMENT-POND COMPANY, OF NEW YORK, N. Y., A CORPORATION OF NEW JERSEY.

MACHINE TOOL.

Application filed March 17, 1924. Serial No. 699,877.

To all whom it may concern:

Be it known that I, JOHN P. BROOKE, a citizen of the United States, residing at Narberth, in the county of Montgomery and State of Pennsylvania, have invented certain new and useful Improvements in Machine Tools, of which the following is a specification.

This invention relates to machine tools and particularly to a key seat drilling or milling machine of the general type illustrated in the accompanying drawing. Such machines are used primarily for milling slots, cutting key-ways and similar operations. The primary object of the invention is to provide an improved machine of this type.

Machining operations such as those above mentioned are more efficiently performed if a lubricant or coolant is flowed over the tool or tools during the cutting operation. The invention illustrated herein provides means for very effectively performing such function. It is accordingly another object of the invention to provide an improved machine tool bed particularly adapted to receive this lubricant as it drains from the tools and conduct the same to a trough from which it may again be pumped to the tools, the construction preferably being such that the cutting chips are automatically separated from the lubricant.

A further object of the invention is to provide a machine tool bed as above described with improved means thereon for supporting the tool carriage and work holders and improved means cooperating therewith for driving opposed cutter spindles carried by the carriage.

With the above and other objects in view, my invention consists in the features of construction and operation set forth in the following specification and illustrated in the accompanying drawing. In such drawing annexed hereto and forming a part of this specification, I have shown the preferred embodiment of my invention but it will be understood that the invention can be otherwise embodied and that the drawing is not to be construed as defining or limiting the scope of the invention, the claims appended to this specification being relied upon for that purpose.

Referring to the figures of the drawing:

Figure 1 is a plan view of my improved machine tool bed.

Fig. 2 is a side elevation thereof partially in section.

Fig. 3 is a cross section through the bed on line 3—3 of Fig. 2 and showing the tool carriage and its operating mechanism thereon.

Fig. 4 is a detail sectional view taken on line 4—4 of Fig. 3.

Fig. 5 is a cross section through the bed on line 5—5 of Fig. 2 and showing a work holder mounted thereon.

The machine illustrated and described herein, while not limited to any particular cutting operation, is of the general type shown in Patent No. 28,627, dated June 5, 1860. The most common operation performed by such machines is the cutting of key-seats in shafting, such an operation being illustrated both in the drawings of the said patent and in the drawing accompanying this application. In such operation, the shaft to be cut is secured in a pair of chucks which center and hold the work in proper position between a pair of tool spindles supported on the cutter carriage. The chucks are ordinarily clamped to the bed of the machine, thereby holding the work stationary, while the cutter carriage is slidably mounted in a manner to be traversed along the bed in the cutting operation. The novel features of my invention in connection with this machine will become apparent as the description proceeds.

The proper lubricating and cooling of the tools in operation is a feature of primary importance in my invention and the bed of the machine illustrated in the drawing and now to be described forms the basis of this improvement. This bed which is adapted to rest on a base 1 comprises a body portion 2 having a pair of ways 3 and 4 extending along the opposite sides of the top portion thereof. The bottom portion of the bed, as illustrated, is provided with a pair of troughs 5 and 6 integral with the bed and extending along the opposite sides thereof beneath and parallel with the ways. The bed between and beneath the ways is preferably formed into a trough 7 for catching chips and lubricant dropping thereinto.

Between the trough 7 and trough 6, the bed is cored to provide two channels 8 for conducting the lubricant and chips falling thereinto downwardly into the trough 6. A communicating channel 9 is also provided in the bed between the troughs 5 and 6 adjacent each end of the bed whereby lubricant flowing into the trough 6 can flow therefrom into the trough 5. A shoulder 10 is provided in each of these channels 9 adjacent the trough 6 whereby chips and sediment which settle to the bottom of the trough 6 do not flow into the trough 5 with the lubricant.

15 The outer top surface 11 of each way is inclined inwardly and downwardly whereby any lubricant dropping thereon will drain inwardly into the trough 7. The tool carriage 12 is slidably mounted on these surfaces of the ways and is adapted to be traversed therealong by a screw 13 journaled in bearings 14 and 15 at the ends of the bed and threadedly engaging a nut 16 secured to the carriage. The inner portions 20 of the ways project toward each other in a manner providing opposed upper and lower parallel horizontal clamping surfaces 17 and 18. The work holder 19, illustrated in Fig. 5 and hereinafter described, is adapted to 25 be clamped to these surfaces.

Transversely slidable on the carriage respectively above the ways is a pair of tool slides 20 respectively rotatably supporting tool spindles 21 and 22 therein, milling 30 tools 21' and 22' being illustrated as mounted in the spindles. The outer ends of the spindles 21 and 22 are respectively splined to slide through driving gears 23 and 24 in gear boxes 25 and 26 mounted on the ends 35 of the carriage. The tool slides are adapted to be automatically fed toward the work by a double threaded screw 27 threadedly connected to the slides and intermittently rotated through gears 28 and a ratchet gear 29 as the carriage reciprocates. The ratchet gear 29 is adapted to be rotated a pre-determined amount in the feeding direction at each end of the carriage stroke by a pair of pawls (not shown) adjustably 40 mounted in the slot 30 on the bed. A hand-wheel 28' is operatively connected to the gearing 28 for manually rotating the screw 27. Such feeding mechanism does not 45 comprise a part of my present invention and is therefore not illustrated in detail herein.

A main driving shaft 31 extends longitudinally of the bed 2 above the trough 5. A bevel gear 32 rotatably journaled in the carriage and splined to the shaft 31 is in 50 mesh with a bevel gear 33 keyed to a shaft 34 extending into the gear box 25. A spur gear 35 on the shaft 34 is operatively connected to the spindle driving gear 23 by means of two intermediate spur gears 36 55 and 37 in the box 25. A shaft 38 mounted

transversely in the carriage is keyed at one end to the spur gear 36 and at its other end to a spur gear 39 in the gear box 26. This gear 39 is in mesh with the spindle driving gear 24. Rotation of the shaft 31 70 is adapted therefore to drive both cutter spindles in all positions of the tool carriage and tool slides.

A lubricating pump 40 is mounted on a bracket 41 secured to the carriage. The supply pipe 42 for the pump extends downwardly into the trough 5. The outlet pipe from the pump branches at 43 and leads therefrom to the pipes 44 which are adjustable to direct the cutting lubricant onto the tools in operation. An over-flow relief valve is provided in the piping at 45. The pump is driven from the main drive shaft 31 through a pair of spur gears 46 and 47, the gear 46 being secured to the hub of the bevel gear 32.

The work holder illustrated in Fig. 5 comprises a body member 19 on which is slidably mounted a pair of work holding and centering jaws 48. A double threaded screw 49 journaled at 50 in the holder is threadedly connected to the jaws and may be rotated by a hand wheel 51 to engage the jaws with the work W. The member 19 rests on the upper horizontal surfaces 17 95 of the carriage ways and a clamping member 52, connected to the member by bolts 53, engages the lower horizontal surfaces 18. By tightening the nuts on bolts 53, the holder can be rigidly secured to the bed. 100

It is thought that the construction and operation of the machine and the advantages of my improvements will be clear from the above description taken in connection with the accompanying drawing. The main drive shaft 31 is continuously rotated from any convenient source, as an electric motor at the end of the bed. This shaft drives both cutter spindles 21 and 22, the pump 40 and the screw 13, the driving connections not being shown. The screw is adapted to be automatically rotated in opposite directions to reciprocate the carriage by suitable reversing mechanism not shown. This carriage reciprocating mechanism, not comprising a part of my present improvements, is not illustrated herein but may be substantially like that shown in the above mentioned patent. As the carriage is reciprocated along the work W, which is clamped in the manner illustrated, the tools are automatically fed deeper into the work at each stroke until the desired depth of cut has been reached. 115

During the cutting operation, pump 40 supplies a lubricant or coolant to the tools through the pipes 44. The lubricant and chips fall from the tools and work directly into the trough 7 from which they pass through the channels 8 into the trough 6. 130

The chips and sediment settle to the bottom of the trough 6 while the lubricant flows over the shoulders 10 into the trough 5. It should be understood that the term "lubricant" is used throughout this specification in its broad sense as meaning any cutting fluid as used in lubricating, cooling, etc.

What I claim is:

1. A machine tool bed comprising a body portion having two lubricant receiving troughs respectively extending horizontally along opposite sides thereof, a carriage supporting way extending along the bed above and parallel with each trough, the bed between and beneath the said ways being formed into a trough for catching lubricant falling thereinto, the bed between the last named trough and one of the first named troughs being formed to provide a lubricant conducting channel therebetween, and the bed respectively adjacent its ends being formed into two channels providing communication between the two first named troughs. 70
  2. A machine tool bed comprising a body portion having two lubricant receiving troughs respectively extending horizontally along opposite sides thereof, a carriage supporting way extending along the bed above and parallel with each trough, means for conducting chips and a lubricant falling between the ways to one of the troughs, and means providing a communicating channel between the two first named troughs and so constructed that the chips remain in the said one trough while the lubricant flows to the other trough. 80
  3. A machine tool bed comprising a body portion having two lubricant receiving troughs respectively extending horizontally along opposite sides thereof, a carriage supporting way extending along the bed above and parallel with each trough, and means for conducting chips and a lubricant falling between the ways to one of the troughs, the bed between the troughs being constructed to form a communicating channel therebetween and having a shoulder for preventing chips from moving with the lubricant from the said one trough to the other trough. 90
  4. In a milling machine, the combination of a bed having a lubricant receiving trough formed integrally therewith and extending horizontally along one side thereof, a carriage supporting guideway extending along the bed above and parallel with the trough, a tool carriage slidably mounted on the guideway, a pump carried by the carriage and adapted to force a lubricant from the trough to a tool carried by the carriage, and means integral with the bed providing a channel for conducting such lubricant to the trough as it falls from the tool. 100
  5. In a spline milling machine, the combination of a bed having a pair of carriage supporting ways extending along opposite sides thereof, the outer top surface of each way being inclined downwardly and inwardly whereby any lubricant dropping thereon will drain inwardly and the inner portions of the ways projecting toward each other in a manner providing opposed upper and lower clamping surfaces, a tool carriage slidably mounted on the said outer top surfaces of the 110
- ing trough extending horizontally along one side thereof, a pair of carriage supporting ways extending along opposite sides of the bed above and parallel with the trough, a carriage slidably mounted on the ways, two tool spindles carried by the carriage respectively above the ways, a pump carried by the carriage adjacent the trough and adapted to force a lubricant from the trough to the tools carried by the spindles, a shaft extending along the bed adjacent the trough, operative connections for driving the pump and spindles from the shaft, and means providing a channel for conducting the lubricant to the trough as it falls from the tools. 120
6. In a spline milling machine, the combination of a bed having a pair of carriage supporting ways extending along opposite sides thereof, a carriage slidably mounted on the ways, two tool spindles carried by the carriage respectively above the ways, a shaft extending along the bed parallel with the ways, a shaft in the carriage having a splined driving connection with the first shaft, a plurality of spur gears operatively connecting the second named shaft with the adjacent spindle, a shaft carried by the carriage and keyed to one of such gears, and a plurality of spur gears operatively connecting the last named shaft to the other 130
7. In a spline milling machine, the combination of a bed having a lubricant receiving trough extending horizontally along one side thereof, a pair of carriage supporting ways extending along opposite sides of the bed above and parallel with the trough, a carriage slidably mounted on the ways, two tool spindles carried by the carriage respectively above the ways, a pump carried by the carriage adjacent the trough and adapted to force a lubricant from the trough to the tools carried by the spindles, a shaft extending along the bed parallel with the ways, a shaft in the carriage having a splined driving connection with the first shaft, a plurality of spur gears operatively connecting the second named shaft with the adjacent spindle, a shaft carried by the carriage and keyed to one of such gears, a plurality of spur gears operatively connecting the last named shaft to the other 140
8. In a machine tool, the combination of a bed having a pair of carriage supporting ways extending along opposite sides thereof, the outer top surface of each way being inclined downwardly and inwardly whereby any lubricant dropping thereon will drain inwardly and the inner portions of the ways projecting toward each other in a manner providing opposed upper and lower clamping surfaces, a tool carriage slidably mounted on the said outer top surfaces of the 150

ways, and a work holding member mounted on the said inner portions and adapted to be clamped thereto.

9. In a machine tool, the combination of
5 a bed having a pair of carriage supporting
ways extending along opposite sides thereof,
the outer top surface of each way being in-
clined downwardly and inwardly whereby
any lubricant dropping thereon will drain
10 inwardly and the inner portions of the ways
projecting toward each other in a manner
providing opposed upper and lower parallel

horizontal clamping surfaces, a tool carriage
slidably mounted on the said outer top sur-
faces of the ways, a work holding member,¹⁵
mounted on the said inner portions and
adapted to be clamped against the said
opposed horizontal surfaces, and a pair of
opposed clamping jaws on the work holding
member for gripping a work piece there-²⁰
between.

In testimony whereof, I hereto affix my
signature.

JOHN P. BROOKE.
